UNITED STATES PATENT OFFICE.

GEORGE RAMSEY, OF BROOKLYN, NEW YORK, ASSIGNOR TO ANCHOR CAP AND CLOSURE CORPORATION, OF BROOKLYN, NEW YORK, A CORPORATION OF NEW YORK.

CLOSURE-APPLYING MACHINE.

Application filed March 10, 1924. Serial No. 698,205.

This invention relates to sealing machines for sealing tumblers, jars and the like and more particularly relates to automatic feeding and transfer mechanism whereby the containers are positioned automatically beneath the capping head of the sealing machine.

The general object of the present invention is the provision of a capping machine characterized by a cap-applying mechanism operative in synchronism with transfer mechanism for positioning packages to be sealed beneath the capping mechanism.

A further object of the present invention is a mechanism as specified wherein the transfer and feeding mechanism comprises devices for transporting a package from a receiving zone to the capping zone, and from the capping zone to the delivery zone, the arrangement of parts being such that the movements or manipulations to which the packages are subjected prior to the capping operation are reduced to the minimum in number, degree, and speed, commensurate with efficient operation.

A still further object of the present invention is the provision of a device as specified which is adapted for efficient operation on different packages representing a maximum variation in sizes.

A still further object of the invention is the provision of a commercial machine of the type described which is adapted to be installed in conjunction with any of a variety of forms of endless belt conveyors now commonly employed in packing plants, without the necessity for alteration of the machine or of the conveyor. In this connection it is also an object of the invention to provide such a machine which is in effect selfcontained, so that it may be set up in association with an endless conveyor when desired, and removed from such association when the conveyor or the handling table is desired for use in other ways.

This invention possesses many other and advantageous features, some of which, together with the foregoing, will be set out more at length in the following description wherein will be outlined in full that form of invention which I have selected for illustration in the drawings accompanying and forming a part of the present specification.

In the drawings and the specification I have described only the preferred form of my

generic invention, and it is to be understood that I do not limit myself to such form because my invention may be embodied in a multiplicity of forms, each being a species of my invention, it being understood by the claims succeeding the description of my invention I desire to cover the invention in whatsoever form it may be embodied or practiced.

Figure 1 is a front view showing the capping machine and transfer mechanism.

Figure 2 is a side view of the machine with parts broken away to more clearly illustrate the mechanism for operating the transfer device.

Figure 3 is a detail view showing the operating mechanism for turning the transfer device.

Figure 4 is a plan view of the transfer wheel.

Figure 5 is a view illustrating more or less diagrammatically the operation of the complete conveyor and transfer devices.

The most common practice in the art of applying seals to tumblers and jars is to manually place the tumbler or jar, with the cap thereon, in the zone of action of the sealing device and after the seal is completed to manually remove the sealed package. It is obvious that occasionally the operator will fail to position the package at the proper time and the sealing machine must either be stopped or run empty; it is also obvious that packages will be inaccurately positioned in the sealing zone and that improper seals may be thereby formed. Furthermore, these machines are usually run in connection with a filling machine and for economically operating both machines, it is necessary that the operator at one machine shall possess the same speed and efficiency as the operator at the other machine, otherwise the one machine is held back from operating at its full capacity in order not to overrun or overload the other machine.

The present invention is designed to form a continuously operable mechanical organization adapted to operate behind a filling machine, and having its movements so articulated that it is not dependent upon manual operations. To this end the present invention comprises a machine which is adapted to cooperate with a traveling belt utilized to transport packages from a filling station to a labeling, washing, packing, or other

station, in such fashion as to take the packages from the belt or conveyor to a position where the capping or sealing operation is performed upon them and then replace the sealed packages on the conveyor or belt, so that a complete harmony is maintained in the movements by which the package is transported between stations. To accomplish this operation, the transfer mechanism is timed to operate with the capping mechanism and the operation of the entire machine may be synchronized with the conveyor. The type of sealing machine which has been selected for illustration is a type which operates merely by pressure to apply a cap similar to that described in the Townsend patent, No. 1,231,090, although it is obvious that the conveying and transferring mechanism may be operated with other types of closures and sealing devices.

Referring now to the drawings, and more especially to Figure 5, which is a diagrammatic view illustrating a complete cycle of operations, the containers X are positioned as at A beneath a suitable filling device 1 at which point the containers are filled and then are gently slid on to the conveying belt 2 which passes around pulleys 4 and 5 in association with a supporting table 8, and over the belt-tightening pulleys 6 and 7. The belt is driven by any suitable motive power such as motor 3 and gearing 3^a to travel in the direction of the arrows, thereby conveying the packages from the filling station A through the station B, at which point the caps Y may be placed in position on the containers. The capped containers continue to move on to the station C where the package is removed from the conveyor belt 2 and the cap is sealed on the package, and then the package is replaced on the conveyor belt 2 and travels on to the station D which may be a packing table from which the sealed packages Z are packed for shipment.

A more detailed description of the preferred form of the invention will now be made. The capping machine comprises a machine frame 9 which may carry a suitable electric motor 10, on the shaft of which is mounted a small pinion 11 which engages a large idler wheel 12 that is carried on an idler shaft 14 and which is mounted in a bearing 15 on the main frame 9. This idler shaft 14 also carries an idler pinion 16 which meshes with a main drive wheel 17 carried by a main drive shaft 18 that is mounted in a bearing 19 also formed in the main frame 9. The main shaft carries an actuating member 20 of a Geneva movement and the member 20 comprises a dwell cam 21 adjacent which is mounted an actuating roller 22. The driven member 24 of the Geneva movement is provided with curved cam surfaces 25 adapted to engage the circular

dwell cam 21, and the member 24 is also provided with four open slots 26 each adapted to receive the roller 22.

The driven member 24 of the Geneva movement is mounted on a short shaft 27 that is also mounted in a bearing 28 on the main frame 9. The Geneva movement is so constructed that when the main drive shaft 18 makes a complete turn, the short shaft 27 makes a quarter turn and the movement of turning the short shaft 27 is first gradually positively accelerated and then a gradually negatively accelerated movement. The reason for this is the fact that the roller 22 engages the outer portion of one of the slots 26 and as the roller proceeds on its path it approaches the bottom of the slot thereby coming nearer to the axis of rotation of the shaft 27. This roller begins its effective driving movement at a long leverage, which leverage gradually shortens to the middle of the driving movement and then lengthens again at the end of the driving movement. Since the movement of the shaft 18 is a steady, uniform movement, it therefore will be seen that a variable movement is imparted to shaft 27. This variable movement is desirable and important as will later be explained. The shaft 27 carries on its inner end a bevelled gear 29 which meshes with a similar bevelled gear 30 mounted on a vertical shaft 31 which rotates in the bearing 32 on the main frame and carries at its lower end a pair of collars 34 and 35 which are pinned to the shaft 31. These collars may be recessed to form pockets in which are mounted driving pins 36. A transfer wheel 37 is carried by the shaft 31 and is mounted between the collars 34 and 35 and secured with the driving pins 36 to the collars 34 and 35 to fixedly and securely maintain the transfer wheel 37 in definite relation to the vertical shaft 31. It is to be observed that by this arrangement the transfer wheel and its operating shaft are supported and suspended entirely above the conveyor belt, so that the latter may traverse the axis of the wheel without diversion from a straight path in either horizontal or vertical direction. This arrangement also provides a desirable clearance between the belt and wheel which, facilitates the cleansing of the parts over which the vessels are moved, as well as desired adjustments or removal of parts. The transfer wheel may be formed in different manners and of different constructions, but preferably it comprises a pair of sheet metal members 38 and 39 that are riveted together at the hub and are separated to form pairs of arms 40 and 41. These arms preferably are provided with segment end faces, and pockets 42 are provided between the arms. Bolts 44 are set in the corners of the arms and carry stirrups 45 which preferably are made of sheet metal

and therefore are slightly resilient so as not to break or chip glass containers. These stirrups are adapted to be changed to fit different sized packages that are to be sealed.

- Preferably the main frame is supported by pairs of supporting legs 46 and 47 which are bolted to the main frame and which are spaced apart so as to permit their en-
gaging a supporting table 8 to the side of the conveyor belt 2 so that the latter may travel directly beneath the transfer wheel 37, which movement of the conveyor belt transports the packages directly into the package receiving portions of the wheel as is indicated in Figure 4. By regulation of the driving means the speed of the main shaft 18 may be coordinated with the travel of the conveyor belt 2 so that when a package is positioned in a stirrup, the Geneva movement operating through connected parts turns the transfer wheel one-quarter turn and positions the package beneath the sealing mechanism, which will hereinafter be described. In the meantime, if another package is transported by the belt and contacts with the ends of the arms 40 and 41, such package will be delayed and then carried into the next receiving stirrup pocket. In order to assist in maintaining the packages in the desired paths of transfer, suitable guides 48 may be provided as is indicated in Figure 4.

From the foregoing, it will be noted packages being transported in a straight line by the conveyor belt are moved from the belt to the capping station under the member 56 by a single continuous movement imparted by the transfer wheel 37, which, together with the fact that the Geneva movement produces a gradual start and gradual stop of the package, reduces to a minimum the possibility of slopping or spilling the contents before the package is closed. It will be noted further, that the pockets 42 are presented to the approaching packages directly in alignment with their direction of movement, so that each package is automatically seated in the pocket to its full depth. The packages are removed from the belt in a direction substantially at right angles to its movement, which insures their retention in the pockets, and their positive movement by lateral pressure of the pockets to accurate position under the capping device, thus dispensing with the adjustment of guides for each particular size of package.

Referring now to Figures 1 and 2, it will be noted that the main shaft 18 carries on its forward end a crank arm 49 which is connected by means of a pitman 50 with an adjustment sleeve 51 which is adapted to be clamped in predetermined positions on a plunger rod 52 which is mounted to reciprocate in a bearing 54 which likewise is

formed of a part of the main frame 9. The lower end of this plunger rod is recessed to provide a guide for a stem of a capping head 56. The stem 55 carries a cross pin 57 which is mounted to reciprocate in slots 70 58 in the lower end of the plunger rod 52. The cross pin 57 is firmly maintained in lowermost position by means of a spring 59 which is constructed to yield when the head 56 has completely seated a cap. The adjustment sleeve 51 enables the head 56 to be raised or lowered so that its zone of operations may accommodate packages of different heights. While the transfer wheel 75 is so constructed as to effectively handle packages of different heights, it is also obvious that transfer wheels adapted to different sized packages may be easily interchanged on the vertical shaft by driving out the pins which hold the retaining collars 34 and 35 80 85 and substituting one transfer wheel for another. Likewise the stirrups 45 may be easily changed by removing the bolts 44 so that these stirrups may be made to accommodate packages of different sizes and shapes, so that the device is operable effectively upon packages of different heights, shapes and sizes. It will be observed that a machine constructed in the manner above described constitutes substantially a self-contained unit which may be shipped and handled in an entirely assembled condition and may be installed in conjunction with various forms of belt conveyors. By virtue of the fact that all of the operating parts are carried in a unitary frame and are supported entirely above the handling table, the machine may be placed in any desired adjustment relative to the conveyor, and by virtue of its unitary structure and removable mountings, may be placed in position and removed at will, permitting the employment of the conveyor for a variety of uses.

Having thus described my invention, what I claim is:

1. A compact unitary capping mechanism comprising: a frame including supporting members adapted to straddle a conveyor belt; cap applying means establishing a capping station; transfer means suspended between said supporting members, said transfer means being adapted to transfer articles from a straddled conveyor belt to the capping station and then return them to the conveyor belt; and means carried by said frame to actuate said cap applying means and said transfer means.

2. A compact unitary capping mechanism comprising: a frame including supporting legs adapted to straddle a conveyor belt; a capping head carried by said frame, said capping head establishing a capping station; a rotary transfer device suspended between the supporting legs, said transfer device being adapted to transfer articles

110

115

120

from a straddled conveyor belt to the capping station and then return them to the conveyor belt; and a motor mounted on said frame and connected to actuate said capping head and said transfer device.

3. A compact unitary mechanism comprising: a frame including supporting members adapted to straddle a conveyor belt; a cap applying head carried by said frame, 10 said head establishing a capping station and being adjustably mounted to adapt the machine to seal packages of different heights; transfer means suspended between said supporting members, said transfer means being adapted to transfer articles from a straddled conveyor belt to the capping station and then return them to the conveyor belt; and means carried by said frame to ac- 15

tuate said cap applying head and said transfer means.

4. A compact unitary capping mechanism comprising: a frame including a base, supporting members on said base adapted to straddle a conveyor belt on said base; cap applying means carried by said frame, said cap applying means establishing a capping station; a vertical shaft mounted in said frame; a rotary transfer device affixed to the lower end of said shaft, said transfer device being adapted to transfer articles 20 from a straddled conveyor belt to the capping station and then return them to the conveyor belt; and means carried by said frame to actuate said cap applying means and said transfer device.

GEORGE RAMSEY.
